OF NEW YORK COUNTY, NEW YORK

SPEED BOAT

Application filed June 27, 1928. Serial No. 288,576.

This invention is a speed boat, which is pneumatically propelled, by ejecting air rearwardly.

In many types of pneumatically propelled boats, where air or other gases are projected rearwardly, the projected fluids are ejected below the water level. In the present invention, the air streams or fluid streams are projected into the forward ends of longitudinal 10 channels on the outside of the boat, and then projected from the rear of the boat just above the surface of the water. The final projection at the rear is a projection of the air stream into air rather than into water and 15 is one of the very important characteristics of this invention.

While air or other gases may be used, the practical thing to use is air; it should be understood that the term air as used in this 20 specification includes other appropriate fluids, as may prove suitable.

The hull of the speed boat is provided with a plurality of grooves on the exterior thereof which extend substantially longitudinally of 25 the boat and open at the stern, above the water line. The invention is primarily applicable to speed boats, which have only a slight draft.

In the prior art, where the air is ejected below the water line, the water imposes a 30 very considerable resistance which creates so much back pressure that a satisfactory air flow along the channels is not attained. Furthermore, if a large quantity of air is ejected 35 below the water level at the stern, the sustaining effect of the water is largely lost, because a mixture of air and water naturally has not the sustaining power of water alone, 40 the result of which is that the stern of the boat will drop too far into the water, and put the bow too far out of the water.

Speed boats tend to ride largely on the 45 stern anyway, and if they are to preserve proper equilibrium and smooth riding, they must ride on solid water at the stern, and not on air bubbles. With the present invention, the bow of the boat does not project out of 50 the water as with many speed boats.

According to this invention, therefore, the grooves, which are of inverted U-shape, are of such a depth that the air projected rearwardly from the grooves is projected substantially at the water level, the projected air 55 passing smoothly out into air, not into water, so that the boat still rides on water.

The grooves are so placed with respect to the water line that the upper third of a groove is filled with air, while the lower two 60 thirds is filled with water.

Since the air leaving the grooves is discharged into air, it can and does travel at high speed. It travels along the grooves at high speed, and while so doing passes along 65 the surface of the water that is within the grooves. There is, of course, friction between the high speed air stream and the surface of the water in the grooves, whereby there is a frictional drag imposed on the surface of the water by the high speed air, which drags the water toward the stern of the boat, the reactive force of this drag of course propelling the boat forwardly.

The air may be supplied to the grooves 75 from the forward ends thereof by any suitable form of blower, centrifugal or other type of pump, driven by any suitable prime mover. Suitable intake pipes are provided for supplying air to the blower or blowers and valve 80 means are provided at appropriate points for controlling the amount of air supplied to the several grooves, for controlling the air flow as may be desired, and for steering the boat.

An important feature of the invention is 85 that the propelling force is not applied largely at the stern, as is the case with most boats, but is applied along the entire length of the boat, that is to say, the propelling forces are entirely within the body of the boat, between 90 bow and stern, and not beyond the stern, as is the case with a screw propeller.

Air intake funnels are provided, so placed 95 as to utilize the reactive forces of the air drawn into the funnels. The funnels preferably face the bow, and are preferably covered with deflectors, which may be cone-shaped, for deflecting water and spray. The powerful suction on the intake pipes tends 100

to draw the boat forwardly, and this forward pull due to the placement of the intake pipes is one of the important features of the invention.

5 These and further details will be more particularly described in the accompanying drawings illustrating the present preferred way for carrying out the invention.

In these drawings,
10 Figure 1 is a bottom plan view of the boat;
Figure 2 is a top plan view;
Figure 3 is a side elevation;
Figure 4 is a section amidships;
Figure 5 is a rear view;

15 Figure 6 is a view showing the travel of the air through the boat, and

Figure 7 is a detail of one of the grooves.

Referring now to the drawings in which similar reference characters indicate similar parts, the speed boat has a hull 5 provided with a substantially flat bottom 6, bow 7 and stern 8. The bottom of the hull on the outside is provided with a plurality of longitudinally extending grooves, here shown as four 20 in number, the outer pair of grooves being shown at 9 and the inner pair of grooves at 10. Any desired number of grooves could, of course, be used. The outer grooves 9 may extend from a point near the bow to the 25 stern, while the inner pair of grooves extends from amidships to the stern. The grooves 9 converge somewhat as shown in Figure 1, to conform with the curvature of the boat at the bow. The grooves are of such depth with 30 relation to the draft of the boat that when the boat is in motion, the water extends up into the grooves about two-thirds of the height of the grooves, as shown in Figure 7, when the upper third of each groove is filled 35 with air. As shown in Figure 4, the general water level of the boat is the same on the outside of the grooves as inside of the grooves, and as mentioned above, is about two-thirds of the distance from the bottom 40 of the grooves to the top.

From this it will be apparent that air passing along the grooves is finally projected rearwardly substantially at the water level, the air leaving the grooves being projected, 45 not into water, but into air, so that it escapes freely.

Air under pressure is supplied to the forward ends of the grooves by suitable blower means, which are illustrated more or less diagrammatically. Such blower means could take many forms, the form here shown comprising a pair of centrifugal blowers 11 mounted on a common shaft 12, the blowers 50 being connected by pipes 13 to the grooves 9.

The blowers 11 may be driven from any suitable type of power plant, such as the engine 15, which, through a shaft 16 and transmission mechanism 17 and 18 drives the shaft 55 12 and thus drives the blowers.

Air is supplied to the inner pair of grooves 10 by a pair of blowers 20 mounted on a common shaft 21 which is in turn driven by the engine 15, shaft 16 and transmission mechanism 22 and 23. Air from the blowers 20 is led to the grooves 10 through pipes 24.

The air intake means for the several blowers will now be described. Air is supplied to the forward blowers 11 from an intake pipe having an intake mouth 26 facing toward the bow. Air entering this intake mouth passes downwardly through the vertical part 27 of the pipe and then passes forwardly through the pipe 28 into the blower. A spray deflecting shield 29, conical in shape, is placed in front of the intake mouth 26. The amount of air supplied to the grooves 9 is controlled by valves 28a in the intake pipes 28. The parts just described are duplicated for each of the blowers 11.

Air is supplied to the blowers 20 amidships by a pipe having an intake mouth 30 facing toward the bow, the air entering this pipe passing downwardly into the part 31 and then forwardly through a pipe 32 to the blower. A spray deflecting shield 33 conical in shape is placed in front of the intake mouth 30. The amount of air supplied to the grooves 10 is controlled by the valves 32a in the pipes 32. The parts just described are duplicated on both sides of the boat for the two blowers 20. The intakes just described are located on either side of the cockpit 34, as shown in Figure 2.

In order to reverse the boat, short grooves are provided which blow the air forwardly. In the side of the boat amidships, there is a cut-out portion 35, the forward end of which gradually curves outwardly toward the side wall of the boat. This cut-out portion is normally closed by a swingable block 36, provided with a curved portion 37. In normal running of the boat, the block 36 is, as shown in full lines in Figure 1, flush with the side of the boat. It is mounted on a pivot rod 38, vertically disposed, so that it may be swung outwardly as shown in dotted lines in

Figure 1 and when it is thus swung outwardly, its vertical wall 37 cooperates with the cut-out portion 35 to form a forwardly opening groove out of which air is blown from a pipe 39 connected to a blower 40, driven by a motor 41, or which may be connected up by means of any suitable mechanical means to be driven by the motor 15. The pivot rod 38 is controlled by a handle 42 so that it may be swung in and out as desired. The air intake means for the blower 40 comprises an air intake mouth 43 positioned near the bow and facing the stern, the air that enters this

intake mouth passing along the pipe 44 to the blower. A spray deflecting shield 46, preferably conical in shape, is placed just in front of the intake mouth. The parts just described are duplicated on the other 125 130

side of the boat. If it is desired to back the boat in an arc only one of the blocks or shields 36 is swung outwardly. If both are swung outwardly and the blowers 40 operated the boat would back in a straight line.

5 In operation, the main blowers 11 and 20 supply air to the four main grooves, the air being first projected into the forward ends of the grooves, and then passes at high speed 10 along these grooves and is then finally projected at high speed at the stern, above the water level.

The surface of the water being about two-thirds up into the grooves, there is necessarily 15 friction between the high speed air in the grooves and the surface of the water, the air dragging the water toward the stern, the reactive force of which of course tends to propel the boat forwardly.

20 The air from the grooves being discharged above the water level, into air, there is no bubbling at the stern or undue resistance that would be present if the air was ejected below the water level.

25 While the grooves 9 extend for substantially the length of the hull, it should be understood that the boat could be propelled by grooves of lesser length, as for example, by the grooves 10 alone.

30 Another important feature is that the propulsion is entirely within the body of the boat, rather than largely at the stern as is the case with the ordinary screw propeller. The grooves extend for substantially 35 the length of the boat and exert a propelling force substantially the entire length of the boat.

The placement of the air intake means 40 serves also to aid in propelling the boat. The powerful suction exerted by the blowers on the forwardly opening intake mouths serves to draw the boat forwardly, and so a propelling effect from this source is thereby attained.

45 This invention is capable of application to the hulls of flying boats and seaplanes which are essentially high speed craft.

While I have illustrated my invention in some detail it should be understood that this 50 disclosure is purely illustrative and that it may be carried out in other ways, as falling within the scope of the following claims.

I claim as my invention:

1. In an air propelled boat, the combination 55 of a hull provided with spaced grooves extending substantially longitudinally thereof, the grooves opening downwardly for substantially their entire length, and power operated blowing means for supplying air to the forward ends of the longitudinal grooves, the grooves opening at the rear of the hull, above the water line, whereby the air in the grooves travels at high speed while in the grooves and is discharged 60 at high speed directly into air just above the surface of the water at the stern, and an air intake pipe for the blowing means extending for a substantial distance toward the stern from the blower and then bent upwardly and forwardly to provide an intake mouth opening toward the bow.

above the surface of the water at the stern, the boat when moving riding on the portions of the hull between the grooves, and being propelled solely by the ejection of air at the stern.

2. In a high speed boat, the combination 70 with a hull provided with downwardly opening grooves extending substantially longitudinally thereof, the grooves being spaced apart with solid portions of the hull of substantial width between the grooves, on the bottom and outside thereof, means for supplying air under pressure to the forward ends of said grooves, the grooves opening at the stern, above the water line, whereby 75 the air travels at high speed along the grooves and imposes a frictional drag on the surface of the water in the grooves, the air being discharged at high speed directly into air at the stern of the boat, above the water 80 line, the boat when moving riding on the solid portions of the hull between the grooves and being propelled solely by the rearward ejection of air.

3. In a high speed boat, the combination 85 with a hull provided with grooves extending substantially longitudinally thereof, the grooves being spaced apart with solid portions of the hull of substantial width between the grooves, on the bottom and outside thereof, means for supplying air under pressure to the forward ends of said grooves, valved means for controlling the air supplied to the several grooves, the grooves opening at the stern, above the water line, 90 whereby the air travels at high speed along the grooves and imposes a frictional drag on the surface of the water in the grooves, the air during its travel along the grooves being 95 above the water level and being discharged at high speed directly into air at the stern of the boat, above the water line, the boat when moving riding on the solid portions of the hull between the grooves and being propelled solely by the rearward ejection of air.

4. In an air propelled boat, the combination 100 of a hull provided with grooves extending substantially longitudinally thereof, power operated blowing means for supplying air to the forward ends of the longitudinal grooves, the grooves opening at the rear of the hull, above the water line, whereby the air in the grooves travels at high speed while in the grooves and is discharged 105 at high speed directly into air just above the surface of the water at the stern, and an air intake pipe for the blowing means extending for a substantial distance toward the stern from the blower and then bent upwardly and forwardly to provide an intake mouth opening toward the bow.

5. In an air propelled boat, the combination 115 of a hull provided with grooves ex-

tending substantially longitudinally thereof, the grooves being built into the hull so that when the boat is in the water the upper part of the grooves is above the water line, 5 power operated blowing means for supplying air to the forward ends of the longitudinal grooves, the grooves opening at the rear of the hull, above the water line, whereby the air in the grooves travels at high speed 10 while in the grooves and is discharged directly into the air just above the surface of the water at the stern, an air intake pipe for the blowing means, extending for a substantial distance toward the stern from 15 the blower and then bent upwardly and forwardly to provide an intake mouth opening toward the bow, and a spray deflecting shield in front of said intake mouth.

6. In an air propelled boat, the combination 20 of a hull provided with grooves on the outside thereof extending substantially longitudinally thereof and opening at the rear of the boat above the water line, the grooves extending upwardly into the hull so that 25 when the boat is at rest in the water the upper parts of the grooves are above the water line, blowing means in the bow for supplying air to certain of said grooves, and blowing means amidships for supplying air to 30 other grooves, the air from the several grooves being discharged at the stern of the boat, above the water line.

7. In an air propelled boat, the combination 35 of a hull provided with grooves on the outside thereof extending substantially longitudinally thereof and opening at the rear of the boat above the water line, blowing means in the bow for supplying air to certain of said grooves, blowing means amidships for supplying air to other grooves, the air from the several grooves being discharged at high speed directly into air at 40 the stern of the boat, above the water line, 45 and an air intake pipe for one of said blowing means extending rearwardly therefrom and provided with a forwardly facing intake mouth.

8. In an air propelled boat, the combination 50 of a hull provided with grooves on the outside thereof extending substantially longitudinally thereof and opening at the rear of the boat above the water line, the grooves being built into the hull so that when the 55 boat is in the water, the upper part of the grooves is above the water line, blowing means in the bow for supplying air to certain of said grooves, blowing means amidships for supplying air to other grooves, the air from the several grooves being discharged at the stern of the boat, above the 60 water line, an air intake pipe for one of said blowing means extending rearwardly therefrom and provided with a forwardly facing 65

intake mouth, and a spray deflecting shield positioned in front of said intake mouth.

9. In an air propelled boat, the combination 70 of a hull provided with grooves on the outside thereof extending substantially longitudinally thereof and opening at the rear of the boat above the water line, the grooves being built into the hull so that when the boat is at rest in the water the upper parts of the grooves are above the water line, 75 blowing means in the bow for supplying air to certain of said grooves, blowing means amidships for supplying air to other grooves, the air from the several grooves being discharged directly into air at the stern of the boat, above the water line, and air intake pipes for the two blowing means, extending toward the stern from the blower. 80

10. In an air propelled boat, the combination 85 of a hull provided with grooves on the outside thereof extending substantially longitudinally thereof and opening at the rear of the boat above the water line, the upper parts of the grooves throughout their entire length being above the water line when the boat is at rest in the water, blowing means in the bow for supplying air to certain of said grooves, blowing means amidships for supplying air to other grooves, the air from the several grooves being discharged at the 90 stern of the boat, directly into air above the water line, and a common power means for operating the blowers. 95

11. In an air propelled boat, the combination 100 of a hull provided with grooves on the outside thereof extending substantially longitudinally thereof and opening at the rear of the boat above the water line, the grooves extending up into the hull so that when the boat is at rest in the water the upper parts 105 of the grooves are above the water line, blowing means in the bow for supplying air to certain of said grooves, blowing means amidships for supplying air to other grooves, the air from the several grooves being discharged at high speed directly into air at the stern of the boat, above the water line, and valves for controlling the air supplied 110 to the several grooves. 115

12. In an air propelled boat, the combination 120 of a hull provided with grooves extending substantially longitudinally thereof, the upper parts of the grooves, when the boat is at rest in the water, being above the water line, power operated blowing means for supplying air to the forward ends of the longitudinal grooves, the grooves opening at the rear of the hull, above the water line, whereby the air in the grooves travels at high speed while in the grooves and is discharged 125 at high speed directly into air just above the surface of the water at the stern, and check valves at the forward parts of said grooves. 130

13. In an air propelled boat, the combination 135 of a hull provided with grooves extend-

ing substantially longitudinally thereof and having exit openings above the water line, the upper parts of the grooves throughout the lengths of the grooves, being above the water line when the boat is at rest in the water, some of the grooves projecting air rearwardly for propelling the boat forwardly, other groups projecting air forwardly for backing the boat, and blower means for supplying air to the grooves.

14. In a high speed boat, the combination of a hull provided with substantially straight, longitudinally extending grooves, the boat being of relatively light construction so that the upper parts of the longitudinal grooves, when the boat is at rest, are above the water level, and so that the discharge ends of the grooves are above the water level, and blower means for supplying air under pressure to said grooves, whereby the air from the blower means travels along the grooves at high speed, above the water level, and is discharged above the water level at the stern.

15. In a high speed boat, the combination of a substantially flat-bottomed hull provided on the outside with longitudinally extending, substantially straight, downwardly facing grooves, spaced apart, so that there are solid portions of hull between the grooves, the boat being of relatively light construction so that the upper parts of the grooves are always above the water line, and blower means for supplying air to the forward ends of the grooves, the boat at high speed riding on the solid portions of the hull between the grooves and being propelled solely by the rearwardly discharged air, the air travelling at high speed along the upper portions of the grooves and being discharged at the rear of the boat, above the water line.

16. In a high speed boat, the combination of a hull provided with substantially straight, longitudinally extending grooves, the boat being of relatively light construction so that the upper parts of the longitudinal grooves, when the boat is at rest, are above the water level, and so that the discharge ends of the grooves are above the water level, blower means for supplying air under pressure to said grooves, whereby the air from the blower means travels along the grooves at high speed, above the water level, and is discharged above the water level at the stern, and an air intake for the blower means having an intake mouth facing the bow.

17. In an air propelled boat, a hull provided with longitudinally extending grooves which open downwardly for substantially their entire length, the grooves being spaced apart by intervening solid portions of the hull on which the boat rides when in motion, the grooves being of a depth such that approximately the lower two thirds of a groove

is filled with water while approximately the upper one third is filled with air, and means for delivering air to the forward ends of the grooves, such air creating a frictional drag on the water confined in the respective grooves, and being discharged rearwardly of the hull.

In testimony whereof I affix my signature.
